WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

METER TESTING SWITCH

Application filed January 25, 1928. Serial No. 249,379.

My invention relates to testing switches and particularly to meter-testing switches wherein testing terminals are provided for receiving meter-test connections and wherein by the test coils of a test meter may be properly connected to a circuit containing a standard meter.

An object of my invention is to provide a test switch wherein the operating handle cannot be moved to open position to interrupt the circuit except when all of the test connections have been properly connected to the test terminals within the switch.

A further object of my invention is to provide a meter-testing switch wherein the testing connections are latched in engagement with the test terminals and may be released by movement of the operating handle.

A further object of my invention is to provide a meter-testing switch that may be attached to a switchboard panel with a minimum of effort and which is compact and durable in construction.

A further object of my invention is to provide a meter-testing switch with a housing having removable side walls to facilitate inspection and repair of the switch without necessitating removal from the switchboard and wherein the operating handle is removableably attached to the operating rod within the switch so that it may be removed to prevent unauthorized persons from operating the switch.

These and other objects that will be made apparent throughout the further description of my invention, are attained by means of the testing switch hereinafter described and illustrated in the accompanying drawings wherein,

Figure 1 is a longitudinal section through a meter-testing switch embodying features of my invention.

Fig. 2 is a longitudinal section through the switch taken on the line 11—11 of Fig. 1.

Fig. 3 is a transverse section of the switch taken on the line 111—111 of Fig. 2,

Fig. 4 is a bottom plan view of the switch, showing its connection to a switchboard panel, and

Fig. 5 is a side elevation of the operating rod and the switch carrier block.

Referring to the drawings, the device includes an insulating housing 5 having a pair of integral guides 6 extending longitudinally thereof from the bottom 7 of the housing toward the outer end thereof. The guides serve to support and guide a switch-blade-carrier block 8 which is provided with grooves 9 for engaging the guides 6 and permitting reciprocation of the block within the housing. The block is provided, on opposite sides, with the switch contact blades 11 of the double type which yieldingly engage stationary contact blades 12 that are integral with the terminal straps 13 which are secured, at their inner ends, to terminal studs 14 which project exteriorly of the housing 5 and are threaded to receive terminal clamping nuts 15.

The housing is provided with an insulating cover 16 that is attached to the housing by means of screws 17 which are threaded into a metal insert rod 18 embedded in the insulating housing. The cover is provided with four triangular openings 19 that register with the conductor terminal straps 13 for receiving test-connection terminals 21 indicated by broken lines in Fig. 1, and which are made triangular in cross section so that they can be inserted in the openings 19 in one predetermined position only.

The carrier block 8 is actuated by means of an operating rod 22 to which an operating handle 23, having a threaded stud 24, is attached. The rod 22 is connected to the block 8 by means of a threaded bolt 25 that extends through an opening 26 in the block and provides a lost-motion connection between the operating rod 22 and the switch-blade carrier block 8.

A helical spring 20 surrounds the bolt 25 and is disposed between the inner end of the recess 26 in the block 8 and a washer 27 on the bolt 25. The spring 20 serves to yieldingly retain the switch carrier block in a predetermined position with respect to the operating rod 22 and, when the operating rod 22 is in the closed position shown in Fig. 1, the spring retains the carrier block in such

position that the switch blades 11 engage the contact members 12 and establishes a circuit connection between a pair of the terminal studs 14.

5 It is an object of my invention to provide means for preventing opening movement of the switch blades except when all of the test connections are in operative engagement with their respective conductor terminal straps 13. For this purpose, the cover 16 is provided with two pairs of clamping latches 28 that are pivoted on shafts 29 mounted on lugs 31 that are integral with the cover 16. The clamp latches are provided with projections 32 that are adapted to engage in notches 33 in the test-connection terminals 21 which are triangular in cross-section. The clamps are biased into engagement with the connection terminals by means 20 of spring 34 disposed on opposite sides of the rod 22 to engage the inner ends of the clamp latches 28, as indicated in Fig. 1.

The outer ends of the latches 28 are provided with shoulder pins 35 that engage shoulders 36 on the clamp rod 22 and prevent inward movement thereof so long as the latches are in the positions indicated in full lines in Fig. 1. However, when the test-connection terminals 21 are inserted so that 30 they engage the outer ends of the conductor strap terminals 13, as indicated in broken lines in Fig. 1, the latches 28 are displaced so that the pins 35 no longer engage the shoulders 36. The operating rod 22 may 35 then be forced inwardly by pushing on the handle 23, thus moving the switch blades 11 out of engagement with the contact terminals 12. By reason of this arrangement of latches it is necessary to insert all four test-connection terminals 21 before the switch 40 may be released and moved to open position.

When it is desired to detach the test-connection terminals 21, it is first necessary to 45 retract the clamp latches 28 from engagement with the test-connection terminals. It will be noted that the operating rod 22 is provided with a pair of oppositely disposed inclined cam faces 37 which are engaged by 50 the pins 35 when the operating rod 22 is withdrawn beyond the closed position, as shown in Fig. 1. This movement causes outward movement of the outer ends of the clamp latches 28 and withdraws the projections 32 of the latches out of the notches 33 in the test-connection terminals 21. The switch is closed at this time and, therefore, the test-connection terminals may be withdrawn without interrupting the normal circuit through the test switch. After the connection terminals are released, the rod 22 is permitted to return, under the influence of the spring 20, to the normal position shown in Fig. 1. In operation, the test switch is 65 connected in a load circuit in such manner

that current normally flows through both of the switch blades 11. Opening operation of the switch is precluded by engagement of the pins 35 of latches 28 with the shoulders 36 on the rod 22. When all four test-connection terminals have been properly placed in engagement with the terminals 13, the latches 28 are retracted to permit the operating blades 23 to be pushed inward to disengage the switch blades 11 from the contact jaws 12. 70

The test-connection terminals 21 cannot be removed until the switch blades are moved to closed position and the handle 23 drawn outward to cause releasing movement of the latches 28, by reason of the engagement of the rollers 35 with the inclined surfaces 37 on the rod 22. Therefore, the circuit through the blades 11 must be closed before 75 the test connections can be removed. 80

While I have illustrated but one embodiment of my invention, it will be apparent to those skilled in the art that various changes, modifications, substitutions, additions and omission may be made in the apparatus illustrated without departing from the spirit and 85 scope of my invention as set forth in the appended claims. 90

I claim as my invention:

1. The combination with a testing switch 95 having a movable contact for controlling a circuit and operating means therefor, of a test clip interlocked with the operating means for releasably receiving test terminals for shunting the movable contact and for preventing operation of the contact except when the test terminals are in operative relation to the said clip. 100

2. The combination with a testing switch 105 having a switch contact movable to open and closed positions, and means for yieldingly retaining the switch contact in closed position, of a terminal for receiving a test connection, and a latch for preventing opening movement of the switch contact operable by 110 the test connection and yieldingly retaining the connection in operative position. 115

3. A testing switch comprising a movable switch contact, an operating member having a lost-motion connection thereto, a test terminal for receiving a test connection, a latch for yieldingly retaining the connection in operative position and for preventing opening movement of the operating member and operable by the test connection to release the operating member to permit opening movement thereof. 120

4. The combination with a testing switch 125 having a movable contact, an operating means therefor and a plurality of test terminals for receiving test connections, of means for yieldingly retaining the connections in operative positions and for preventing operation of the said contact except when all of the test con- 130

nctions are in operative connection with their
respective test terminals.

5. A testing switch comprising a casing, a
switch contact member guided for movement
5 therein within predetermined limits, a con-
tact member engaged by the switch contact
member when the latter is in one of its limited
positions, a test terminal, an operating mem-
ber having a lost-motion connection to the
10 switch contact, means for releasably retaining
the operating member in a fixed position and
for releasably holding a test connection, yield-
ing means connected to the operating member
and the switch contact for yieldingly retain-
15 ing the switch contact in the said limited
position, and means actuated by the operating
means for releasing the retaining means.

6. A testing switch comprising a pair of
contacts having test terminals adapted to be
20 engaged respectively by test conductors, a
bridging switch contact member for conduc-
tively connecting the said contacts, a test clip
for each test terminal for releasably engaging
a test conductor and retaining it in contact
25 with its respective test terminal, the said clips
normally engaging the said member and pre-
venting opening movement thereof and being
displaced by the test conductors to permit
opening movement of the member only when
30 the test conductors are in operative position.

In testimony whereof, I have hereunto sub-
scribed my name this 23rd day of January
1928.

WALTER H. SCHRAMM.
